CLAIM

The ornamental design for a protective case, as shown and described.

DESCRIPTION

FIG. 1 is a top, right, front perspective view of a protective case showing the new design;

FIG. 2 is a right, rear, top perspective view of the invention illustrated in FIG. 1;

FIG. 3 is a front view of the invention illustrated in FIG. 1;

FIG. 4 is a rear view of the invention illustrated in FIG. 1;

FIG. 5 is a right side view of the invention illustrated in FIG. 1;

FIG. 6 is a left side view of the invention illustrated in FIG. 1;

FIG. 7 is a top view of the invention illustrated in FIG. 1; and,

FIG. 8 is a bottom view of the invention illustrated in FIG. 1.

The broken lines in the drawings represent portions of the protective case that form no part of the claimed design.

1 Claim, 6 Drawing Sheets
